US00D993938S

(12) **United States Design Patent** (10) **Patent No.:** **US D993,938 S**
Biddle (45) **Date of Patent:** **** Aug. 1, 2023**

(54) **REMOTE CONTROL**

(71) Applicant: **Amazon Technologies, Inc.**, Seattle, WA (US)

D520,495 S 5/2006 Dukerschein et al.
D529,872 S 10/2006 Weitgasser et al.
D531,585 S 11/2006 Weitgasser et al.
(Continued)

(72) Inventor: **Jonathan Howard Biddle**, San Francisco, CA (US)

FOREIGN PATENT DOCUMENTS

(73) Assignee: **Amazon Technologies, Inc.**, Seattle, WA (US)

CN 304505047 2/2018
CN 304588761 4/2018
(Continued)

(**) Term: **15 Years**

(21) Appl. No.: **29/867,835**

(22) Filed: **Nov. 10, 2022**

Related U.S. Application Data

(62) Division of application No. 29/737,572, filed on Jun. 10, 2020, now Pat. No. Des. 969,778.

CLAIM

D32/50, 51, 39-45; D21/333; D11/26

The ornamental design for a remote control, as shown and

CPC H01H 9/35; H01H 9/0242; H01H 9/02;

described.

H01H 9/021; G08C 17/02; G08C 17/00;

DESCRIPTION

A47C 31/008; A61G 13/02; G07C

FIG. 1 is a top, front perspective view of a remote control; FIG. 2 is a bottom, back perspective view thereof;

9/00944

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the remote control that form no part of the claimed design.
